US0D1077093S

(12) **United States Design Patent** (10) **Patent No.:** **US D1,077,093 S**
(45) **Date of Patent:** **** May 27, 2025**

(54) **FITNESS EQUIPMENT**

(71) Applicant: **XAVORK WOOLIAND INC**,
Gresham, OR (US)

(72) Inventors: **Hengjie Gong**, Gresham, OR (US);
Jifeng Xu, Gresham, OR (US)

(73) Assignee: **XAVORK WOOLIAND INC**,
Gresham, OR (US)

(**) Term: **15 Years**

(21) Appl. No.: **29/907,905**

(22) Filed: **Jan. 9, 2024**

(51) **LOC (15) Cl.** **21-02**

(52) **U.S. Cl.**
USPC **D21/673**

(58) **Field of Classification Search**

USPC D21/671, 673, 686, 694, 679, 691, 692

(57) **CLAIM**

The ornamental design for a fitness equipment, as shown and described.

DESCRIPTION

FIG. 1 is a perspective view of a fitness equipment showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof; and,

FIG. 7 is a top view thereof.

The broken lines illustrate portions of the fitness equipment that form no part of the claimed design.

1 Claim, 7 Drawing Sheets
